A. J. MORGAN,
INSULATOR SUPPORT,
APPLICATION FILED MAY 22, 1917.

1,258,802.

Patented Mar. 12, 1918.

INVENTOR,

Andrew J. Morgan,
BY Allen Day, *AS*
ATTORNEYS.

UNITED STATES PATENT OFFICE.

ANDREW J. MORGAN, OF FRAMINGHAM, MASSACHUSETTS.

INSULATOR-SUPPORT.

1,258,802.

Specification of Letters Patent. Patented Mar. 12, 1918.

Application filed May 22, 1917. Serial No. 170,276.

To all whom it may concern:

Be it known that I, ANDREW J. MORGAN, a citizen of the United States, residing at Framingham, in the county of Middlesex, in the State of Massachusetts, have invented a certain new and useful Improvement in Insulator-Supports, of which the following is a specification, reference being had to the accompanying drawings.

10 The immediate object of this invention is to provide a strong serviceable and particularly convenient form of support for glass and porcelain insulators of the class commonly used for supporting telegraph, telephone, and the like wires, my present improvement being specially valuable for attachment to tree trunks or limbs and in other situations where it is not feasible, or otherwise desirable, to provide cross-arms 15 or brackets of any of the ordinary constructions.

My invention is clearly illustrated in the annexed drawings in which Figure 1 is a side elevation of an insulator support embodying my present improvements and Fig. 2 is a plan view of the same. Fig. 3 is an outer end or face view of the complete support and Fig. 4 is a perspective view of the roll which serves as a support for the line 20 wire.

Referring to these drawings the letter *a* indicates a glass or porcelain insulator which may be of ordinary form and construction, as it is my purpose to adapt my 25 newly improved support for use with such insulators. The letters *b* and *b'* denote a strap or clamp-collar whose two parts are hinged at *b* and whose terminals are extended and spaced apart in parallel relation

to each other so as to embrace a bracket *c*, to which they are adjustably clamped by means of a bolt or screw *d*. The bracket *c* is adapted to be bolted or otherwise fastened to a tree or limb, as will be understood by reference to Figs. 1 and 2 of the drawings. 45 The clamp collar *b*—*b'*, by means of which the insulator is suspended, lies snugly within the annular groove in which, ordinarily, the line wire is supported.

50 In the threaded interior of the insulator *a* I screw an eye-bolt *e* and in the eye of said bolt I suspend, by means of "sister hooks" *f*—*g*, a loose pulley or roll *h* which serves as the support for a running wire *k*, the arrangement of the support being such that 55 the wire may render freely on the roll *h* to meet all conditions resulting from expansion and contraction of said wire and the wire is also free to swing or sway laterally a limited distance, the weight of the line wire holding 60 the sister hooks in their locked positions.

By the use of insulator supports embodying my novel features, as recited in the following claim, high tension and other electrically charged wires may be readily supported in safe relation to trees and the like objects. 65

Having thus described my invention, I claim as new and wish to secure by Letters Patent:—

In combination with an insulator of the class referred to, means for adjustably supporting said insulator, and means for suspending a line wire consisting of an eye-bolt 70 removably connected with the insulator, and an idle roll depending from said eye-bolt and free to sway in every direction. 75

ANDREW J. MORGAN.
